METHOD OF MAKING VALVES

Robert Jardine, Detroit, Mich., assignor, by mesne assignments, to Eaton Manufacturing Company, Cleveland, Ohio, a corporation of Ohio

Application October 14, 1931, Serial No. 568,771

2 Claims. (Cl. 29—156.7)

This invention relates to valves and more particularly to the poppet type of valve used in internal combustion engines.

One object of the invention is the provision of 5 a valve having a hollow steel head portion filled with material such as copper having superior heat conducting properties.

Another object of the invention is the provision of a valve having a steel shell portion formed by 10 swaging the steel when filled with a ductile material.

Another object of the invention resides in the method of making a valve in which a steel bar is drilled, the hole being subsequently filled with 15 a ductile heat conducting material, the filling material being swelled out in the valve head by a forging operation to provide a hollow steel head having a filling of the heat conducting material.

20 Other objects and advantages of the invention will be apparent from the following description, the appended claims and the accompanying drawing, in which

Fig. 1 is a longitudinal cross-sectional view of 25 a valve formed in accordance with the present invention;

Fig. 2 is a cross-sectional view of the valve body during its course of manufacture;

Figs. 3 and 4 are cross-sectional views showing 30 the head end of a valve at different stages of a modified method of procedure; and

Figs. 5 to 9 illustrate different steps in the course of construction of a valve in accordance with another modification of the method of procedure.

Referring more particularly to the drawing by reference numerals, 10 designates generally a hollow valve adapted to be used in internal combustion engines, and especially adapted for use 40 as an exhaust valve. In such type of valve it is desirable to conduct the heat rapidly from the valve head to the valve stem portion so that the operating temperature of the valve head is reduced. In accordance with the present in-

45 vention, the valve comprises a hollow steel shell 11, containing a filling 12 of a ductile material having superior heat conducting properties. As shown in Fig. 1 the filling 12 is flared outwardly within the valve head and fills the chamber provided in the valve stem, the head portion of the filling being of substantially mushroom shape and being encased or enclosed in the hollow steel valve head shell indicated at 13. Since the filling 12 is flared out within the valve head, there will 55 be a comparatively rapid transfer of heat from

the outer steel shell of the head, the intimate contact or bond between the filling 12 and the steel shell providing for the effective transfer of heat so that the heat may be conducted down to the valve stem and transferred to the 5 valve guide.

In the construction of the valve, a steel bar 15 shown in Fig. 2 preferably having one end 16 of considerably greater diameter than the comparatively long and thinner end 17, is drilled so 10 as to provide the hole 18 extending from one end part way through the bar. This hole is then filled with a plug 19 of copper or other suitable material of sufficient ductility so as to be adapted to the subsequent forging operation, and that 15 has superior heat conducting properties. The filling 19 is preferably applied in the form of a bar which is forced within the hole, the length of this filling material being preferably somewhat shorter than the length of the hole so as to 20 provide a small space 20 at the outer end of the steel bar, as shown.

The end 16 of larger diameter is then forged so as to provide a valve head of substantially mushroom shape, the forging operation serving 25 to force the steel into the space 20 and close this space while at the same time radially expanding both the copper filling and the steel shell portion to provide a hollow steel head having the filling of copper as shown in Fig. 1. If 30 the space 20 is not completely closed by the steel any small openings may be filled by welding. During the forging step, the copper filling of the valve head is intimately associated with or bonded or fitted to the steel shell to provide for 35 the effective conduction of heat from the shell to the copper. The heat may therefore be rapidly conducted away from the head and down to the stem portion of the valve during operating conditions, even though the steel shell is 40 an alloy particularly desirable for withstanding the high operating temperatures and the attacking gases that are present in the engine fuel or products of combustion.

In accordance with the structures shown in 45 Figs. 3 and 4, the valve head 21 comprises the steel shell 22 entirely enclosing and encasing the filling 23 of copper or the like, the copper filling being flared out in the valve head to provide for the effective heat transference from the 50 valve head to the valve stem. The steel shell of the valve 21 may be formed by drilling a steel bar 24 almost but not quite down to the larger end 25, this end of the valve being subsequently forged after inserting the bar 26 of copper or 55

similar filling material. The steel shell of the valve head is thus of one-piece integral construction entirely and perfectly sealing the copper filling within it. The stem may of course be machined and finished in any desired manner. When used with the copper filling the space within the valve head and stem, the effective heat transfer during operating conditions is provided for. However, if the copper filling is removed after the valve head is forged, in the manner more fully set forth and claimed in my co-pending application, Serial No. 563,770, filed on even date herewith, the forging of the head when filled with copper is particularly advantageous, providing in a simple way for a steel shell formation of the desired wall thickness.

In accordance with the steps shown in Figs. 5 to 9, the valve is made in a slightly modified manner. 28 designates a steel bar, that is provided with the bores 29 and 30, preferably produced by drilling the bar part way from one end to the other. Between the two bores 29 and 30 there is a frusto-conical or tapered surface 31. A filling of copper or other suitable material is then applied, this filling being suitably shaped so as to fit within both bores, and having a tapered or frusto-conical surface 33 that fits with the surface 31 in the bar. There is an upstanding ring 34 of steel projecting up above the top of the filling 32, and this ring is then forged over and around the filling 32 so as to shape and close this end of the filled bar substantially as shown in Fig. 7. The upper end or closed portion of the filled bar may then be flattened by a suitable forging operation so as to provide a flat circular end 35, and the lower end of the bar is then swaged or forged so as to reduce its diameter and form a stem 36 as shown in Fig. 8, curved outwardly at its upper end as shown at 40 37. The valve head is then forged, being coined to the shape shown in Fig. 9, this forging step expanding the copper and the outer steel shell in which the copper is enclosed so as to provide a substantially mushroom shaped copper filling 45 38 in the steel shell 39 of the valve head which entirely encloses it and which is in close fitting or bonded engagement with it by reason of the forging operation, providing for effective heat transfer from the valve head to the valve stem. 50 In accordance with the method just described the valve stem and the valve seat can then be machined and any necessary or desirable heat treatments given.

While the methods herein described, and the 55 form of construction produced thereby, consti-

tute preferred embodiments of the invention, it is to be understood that the invention is not limited to these precise methods and form of construction, and that changes may be made in either without departing from the scope of the 5 invention which is defined in the appended claims.

What is claimed is:

1. The method of making a valve of the class described comprising forming a chambered piece 10 of steel, with continuous sides, rounded and imperforate at one end and open at the other end, providing a counterbored passage of larger diameter at the open end than at the closed end and with tapering sides joining the passages of 15 different diameter, making a metal core which is larger in cross-sectional area at one end than at the other and fitting the same within the chamber of the steel piece, increasing the diameter of the composite steel piece and core at the 20 end thereof in which the core is of larger cross-sectional area to increase the diameter of the steel and the core and provide a mushroom shaped core encased in steel at the head end of the valve, and elongating the other end into a 25 valve stem in which the core is enclosed by the steel throughout its length.

2. The method of making a metal filled poppet valve comprising drilling a piece of steel to provide a piece with continuous sides and imperforate at one end and open at the other end, drilling an enlarged axial passage at the open end of the steel piece of larger cross-sectional area than the passage adjacent the closed end of the piece and tapering the adjacent ends of 30 the passages from one to the other, forming a metal core of good heat conductivity, having rounded ends and larger in cross-sectional area at the one end than at the other to fit within the chamber and axial passage and fitting the 40 same within the chamber and the axial passage to leave the open end of the passage unfilled, heating the steel piece and forging its terminal or open end so that it is rounded over the end of the core, forging said parts to flatten said terminal end and to elongate the other end of the composite steel piece and core into a valve stem in which the core is enclosed throughout its 45 length in the stem by the steel piece, and forging the flattened terminal end of the valve to increase the diameter of the steel and the core at the head end of the valve and provide a mushroom shaped core encased in steel. 50

ROBERT JARDINE. 55
